ARTHUR L. CURRIER, OF NEW IPSWICH, NEW HAMPSHIRE, ASSIGNOR TO J. W. MOORE MACHINE COMPANY, OF BOSTON, MASSACHUSETTS, A CORPORATION OF MASSACHUSETTS.

APPARATUS FOR DRESSING GRINDERS.

Application filed February 19, 1920. Serial No. 359,869.

To all whom it may concern:

Be it known that I, ARTHUR L. CURRIER, a citizen of the United States, and resident of New Ipswich, in the county of Hillsboro and State of New Hampshire, have invented an Improvement in Apparatus for Dressing Grinders, of which the following description, in connection with the accompanying drawings, is a specification, like 10 letters on the drawings representing like parts.

My present invention is an improved grinding wheel dressing or trueing apparatus and a method of performing the 15 dressing operation. The use of grinding wheels, for sharpening edge tools, cutters, or other work, is now very generally employed in shop practice, and it has become important to dress, reform, clean and true 20 up the working surface of such grinding wheels. In the use of a grinding wheel, such for example as an emery or carborundum grinder, the operating surface or face of the abrasive material becomes quickly 25 filled or clogged by the material on which the grinder is used. Furthermore, in the usual operation of such a grinding tool it is worn unevenly on its face and consequently requires a constant dressing or trueing to 30 restore its even grinding surface, as well as to clean and clear the abrasive in the grinding surface. As the abrasive of such grinding tools is extremely hard, it is difficult to secure a suitable dressing material which 35 will not be quickly worn away, it now being customary to use a diamond dresser. My present invention contemplates the trueing and dressing of such a grinding tool by a novel method and by employing an inexpensive abrasive, such as carborundum, 40 emery or the like similar to that of which the grinding wheel itself is formed. Furthermore, my invention utilizes a novel principle whereby the rotation of the grinding wheel itself will produce a rotative action in the dressing apparatus, so arranged and positioned as to effect a slanting, angular, eccentric, slashing or shearing cut 45 on the grinder. This feature of a shearing 50 cutting action between the dressing tool and the grinder, is most important, as it

automatically trues and trims the entire surface of the grinder, both widthwise and circumferentially, and also cleans or clears the abrasive face of the grinder, removing 55 the filling, if any, and effectually leaving the face of the grinder with a clean, clear, sharp cut abrasive surface. In the prior use of a diamond cutting tool, the abrasive surface was broken off and not left uniformly clean, 60 clear and sharp, whereas in employing my method and with the dresser herein shown and disclosed, I am enabled to produce an ideally sharp reformed and trued abrasive face on the grinder. 65

Additional features are that the clear and sharp cutting action on the grinder is produced by an inexpensive material, viz., carborundum or the like; that the relative motion between the grinder and the dresser 70 is effected by the rotary action of the grinder itself, no belts, pulleys or the like being necessary to actuate the dressing tool; the arrangement, position and operation of the dresser and grinder produce the desired 75 relative action which effects the trueing and sharp cutting; and my novel dressing tool or apparatus is itself maintained with a true surface for subsequent dressing of grinders, and may be in a form which will give long 80 life and great wear to the dresser itself; the dressing tool medium being preferably mounted for rotative action in a convenient holder and on an anti-friction thrust bearing. 85

Referring to the drawings, illustrating my novel method and showing a preferred form of dressing tool,

Fig. 1 is a view partly in cross-section of the dressing tool; 90

Fig. 2 is a fragmentary plan view showing the application of the dressing tool to a grinding wheel;

Fig. 3 is a fragmentary cross-sectional view illustrating the action of the dresser 95 and grinder; and

Fig. 4 is an end view showing the dressing tool in cross-section as applied to a grinding wheel.

It will be appreciated that my dressing tool may be of any size desired and may be mounted other than as a hand apparatus 100

So long as the dressing tool is applied to the grinding wheel to be dressed in accordance with my method, and to effect a shearing cut, retrueing action and the like, 5 my method is carried out. Thus the dresser might be mounted on a movable arm to be swung into and out of position—similar to the jointing tools on a planing machine, the resulting method of action on the grinder 10 being the same as if the dressing tool is applied by hand. As illustrated in the drawings, a grinding wheel is mounted at 1, and the dressing tool at 2. The grinder may be of any desired size and width, being herein illustrated in characteristic proportions. The grinder 1 may be of emery, carborundum or stone, mounted for rotative action as indicated by the arrows 3. Such grinders are usually set in machine shops 15 and power supplied through a pulley or other means rotating the axle of the grinding wheel 1. The dresser tool 2 is preferably formed as a cylinder, and with its edge face 4 positioned or applied to the circumferential face 5 of the grinding wheel 1, eccentrically of the axial center of the dressing tool 2. With this method of application between the two surfaces 4 and 5 and with the grinder 1 rotating and the dressing tool 25 2 rotatable, a rotation of the tool 2 is imparted to it by the rotating action of the grinder 1, the dressing tool being thus automatically rotated in the direction of its arrow 6. As clearly shown in Fig. 4, the resulting action of my method effects a slashing cut on the surface 5 of the grinder, this relative slanting cutting action preserving both surfaces 4 and 5 in prime cutting condition, and furthermore automatically trueing 30 the contacting surfaces of both grinder and dresser and maintaining these surfaces in the desired plane perpendicular to the radius of rotation of each implement.

The dressing tool itself is preferably 45 mounted to rotate freely, and to be held in contact with the grinder as long as desired. As herein shown, the dressing tool 2 is of considerable length, thus giving a relatively long life and wearability thereto. I prefer 50 to form the dressing or carborundum 2 as a cylinder, as shown, with a projecting flangelike portion 10 to aid in securing the same to a plate 11 having a central hub 12 of proper diameter to snugly fit within 55 the circular recess of the flange 10. This enables a washer 13 of greater diameter than the hub 10 and of equal diameter to that of the cylindrical recess to be applied to the hub 12 and secured thereto by a screw 60 14 fitted into a tapped recess in the hub 12. I may also fit a cushion washer 15 between the contacting edge of the plate 11 and the abrasive 2. The plate 11 is secured to or 65 formed with a shaft 16 extending into the handle portion. Preferably this shaft 16 is

fitted within a tubular part 17 secured to the handle 18 and thus affording a long steady bearing for the rotation of the abrasive 2. I prefer to mount the abrasive 2 on a bail bearing raceway, preferably as a thrust 70 bearing between the hub 10 and plate 11, as indicated at 21, and a corresponding raceway 22, the latter mounted within a cup shaped portion 23 of the tubular handle part 17, as clearly shown in Fig. 1. A dust 75 cap or guard 25 may be fitted over the ball bearing portions and secured at its rim by screws 26 to the outer rim part of the plate 11. The mounting just described enables the operator to hold the handle 18 and tubular column or portion 17, thus firmly positioning or alining the abrasive when applying to the grinding tool to be dressed. As soon as the surfaces 4 and 5 of the dresser 80 and tool respectively are brought into contact at one side of the center of rotation of the dressing tool, the continued rotation of the dresser 1 will impart rotation of the grinder 2 and being mounted in a ball bearing this action will require but a minimum 85 of power and makes the dressing tool immediately responsive to the rotating action of the grinder. The operator can move the dresser to and fro across the surface of the grinding wheel, so long as the points of contact are sufficiently at one side of the axis of the dresser to produce the rotation of the latter. Preferably and as herein shown, the dressing tool 2 is formed as a cylinder of sufficiently greater diameter 90 than the surface 5 of the grinder to be dressed, so as to insure the dressing tool entirely covering the grinder surface 5, entirely at one side of the axis of the tool 2. 95

In operation, I find that the hardest grinding wheel will be very quickly trued and reduced by the action of the dresser in effecting its shearing or slashing cut, this slanting or slashing cut preferably being 100 effected by the contact of the grinding surfaces in a line outwardly from the center of the dresser, as clearly shown in Fig. 3, where the upper part of the cylindrical dressing tool 2 is that portion brought into contact with the grinder 1. Furthermore 105 the continued action of the dresser leaves the surface of the dressing tool in sharp, clean and cutting form and ready for a subsequent operation. The entire length of the cylindrical dressing tool member 2 may 110 be used up in this action until the abrasive 2 is worn off or down to the washer 13, and even then may still be employed if the grinding wheel is of less width than the 115 distance between the edge of the washer 13 and the outer surface of the dressing tool, in which case the washer 13 will not be an interfering obstruction.

My invention is further described and 120 defined in the form of claim as follows:

A dressing apparatus of the kind described, comprising a tubular member, a handle secured to one end thereof, an anti-friction bearing mounted on the end of the tube remote from the handle, and a cylindrical abrasive dressing tool secured to the outer end of the anti-friction bearing,

the axes of the cylindrical dressing tool, tubular member, and handle being in alignment with each other.

In testimony whereof, I have signed my name to this specification.

ARTHUR L. CURRIER.
